(57) CLAIM

We claim the ornamental design for a decorative bottle, as shown and described.

DESCRIPTION

FIG. 1 is a front view of the decorative bottle showing our new design;

FIG. 2 is a right side view thereof;

FIG. 3 is a left side view thereof;

FIG. 4 is a rear view thereof;

FIG. 5 is a top plan view thereof; and,

FIG. 6 is a bottom view thereof.

The broken lines are included for the purpose of illustrating a portion of the base of the bottle that forms no part of the claimed design.
